UNITED STATES PATENT OFFICE.

TJERK DYKSTRA, OF SHELDON, IOWA.

OIL BURNER.

Application filed March 10, 1923. Serial No. 624,077.

To all whom it may concern:

Be it known that I, TJERK DYKSTRA, a citizen of the United States, residing at Sheldon, in the county of O'Brien and State of Iowa, have invented certain new and useful Improvements in Oil Burners, of which the following is a specification.

My invention relates to improvements in oil burners that is well adapted for employing fuel of the cheaper grades, the nature of the invention being such as to completely vaporize the fuel before the same passes to the burner nozzles, the invention being further characterized by the high degree of heat obtained in the employment of the burner constructed in accordance with my invention.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:—

Figure 1 is an elevational view of my improved oil burner, together with the supply tank therefor.

Figure 2 is an enlarged detail vertical cross sectional view of the burner.

Figure 3 is a vertical transverse cross sectional view thereof, and

Figure 4 is a detail sectional view of one of the burner nozzles, per se.

Referring to the drawings in detail, my device constitutes the provision of a stand 5 of any desirable construction, there being positioned upon this stand, a pair of vertically disposed nipples 6, the same being formed integral upon the ends of a cross plate 7, this plate being in turn secured as at 8 to the said stand 5. The opposite ends of each of these nipples 6 are screw threaded as clearly shown in Figure 2, and screw threadedly disposed within the lower ends of the nipples are the screw threaded ends 50 of pipes 9, it being of course understood that the said stand 5 is formed with openings in alinement with the nipples, for permitting the engagement of the pipe 9 therethrough. The opposite ends of each of these pipes 9 are connected through the instrumentality of elbows 10, with a cross

pipe 11, this pipe being in turn connected with an oil feed line pipe 12. This oil feed line pipe is equipped with a cut off valve 13, the said feed line extending to an oil tank 14 of a desired capacity.

Disposed within the upper screw threaded ends of each of the said nipples 6 are the lower screw threaded ends of pipes 15, the upper ends thereof being screw threadedly disposed within outlet nipples 16, upon opposite ends of a burner dome 17. This dome 17 is equipped with an outlet pipe 18, the same being pendent therefrom, and connected through the instrumentality of a right angularly extending pipe 19 with a cross pipe 20. As more clearly shown in Figure 4, the ends of this pipe 20 are equipped with elbows 21, each of which carries a burner nipple 22, the same extending vertically for permitting the flame to impinge upon the bottom surface of the said dome 17 for vaporizing the fuel oil therein.

Positioned over the said dome 17 is a flame deflector 23, the same being of considerable depth, and being in the form of an inverted pan-shaped member, and in view of the above description, it will at once be apparent that by opening the valve 13 in the pipe line 12, the oil from the tank 14 will be permitted to flow into the dome 17, the flame from the burner nipples 22 effectively vaporizing the oil therein.

It is believed by me that it will be at once apparent that I have provided a highly improved form of oil burner, and one that is well adapted for burning the cheaper grades of oil, and although I have herein shown and described the preferred embodiment of the present invention, it is nevertheless to be understood that minor changes may be made therein, without departing from the spirit and scope of the invention as claimed.

Having thus described my invention, what I claim as new, and desire to secure by Letters-Patent is:—

An oil burner including a stand for supporting the burner, a cross plate mounted on the stand having an opening in each end extending vertically therethrough, a main oil supply having a pair of branches, each branch being connected with one end of the cross plate and communicating with the opening therein, a pair of hollow risers each having one end mounted in one end of the cross plate and communicating with the opening therein, a hollow burner dome rec-

2
tangular in cross section having the lower outer end portion connected with the risers, and outlet pipes extending downwardly from the central side portion of the dome and terminating in a lateral extension, a pair of burners extending from the end of the lateral extension oppositely in the plane of the riser and toward the riser, and a burner cap mounted over the dome having 10 a downwardly extending skirt portion

spaced from the sides and ends of the dome and extending below the same, whereby the oil will be divided before it reaches the burner, in order to provide for quick vaporization and superheating, preparatory to 15 entering the outlet pipe.

In testimony whereof I affix my signature.

TJERK DYKSTRA.
